UNITED STATES PATENT OFFICE.

JAMES S. THOMPSON, OF PELHAM, NEW YORK, ASSIGNOR TO THE AMERICAN BRAKE SHOE & FOUNDRY COMPANY, OF WILMINGTON, DELAWARE, A CORPORATION OF DELAWARE.

BRAKE-SHOE.

1,369,498.

Specification of Letters Patent. Patented Feb. 22, 1921.

Application filed December 17, 1919. Serial No. 345,536.

To all whom it may concern:

Be it known that I, JAMES S. THOMPSON, a citizen of the United States, residing at Pelham, in the county of Westchester and 5 State of New York, have invented certain new and useful Improvements in Brake-Shoes, of which the following is a specification.

This invention relates generally to brake 10 shoes of that type which are provided with a reinforcing back and reinforcing strips of reticulated metal embedded in the body of the shoe on the edge to the wearing face thereof.

15 The object of the invention is to provide for anchoring the reinforcing strips to the reinforcing back in a novel and simple manner which will facilitate the operation of casting the body on the back and strips, and 20 which will provide a strong and substantial shoe.

25 In the accompanying drawings I have selected a segmental shoe for illustrating the invention, but I do not thereby restrict the invention to this particular type of shoe, for I am aware, and those skilled in the art will readily appreciate as the invention is better understood, that it may be embodied in solid shoes as well as in segmental shoes 30 and in different kinds of segmental and solid car and driver shoes.

In the drawings—

Figure 1 is a side elevation of a segmental car shoe, partly in section, embodying my 35 invention.

Fig. 2 is a cross-sectional view on the line 2—2 of Fig. 1.

Fig. 3 is a plan view of the reinforcing back.

40 Fig. 4 is an edge of the back.

Referring to the drawings, 5 is the body of the shoe which is divided into a plurality of segments 6 by the transverse slots or grooves 7. This body is cast on the ductile 45 metal back 8, and the reinforcing strips 9 of reticulated metal, such as expanded metal, are embedded in the body on edge to the wearing face of the shoe in an inclined position as shown in Fig. 2 or in a perpendicular position as may be preferred.

The reinforcing back 8 is provided with a plurality of transverse depressions 10 spaced apart at intervals between its ends.

In each of these depressions there is a plurality of slits 11 corresponding to the number of strips 9 and extending lengthwise of the back. The strips are projected into these slits 11, and pins 12 are engaged with the strips and the back to anchor the strips to the back. The strips are thus assembled 60 and anchored to the back and then the body metal is cast thereon. The body and back are securely anchored together by the pins 12, and as all parts of the body are held together by the strips, there will be no possibility of any parts of the shoe becoming detached in event the shoe is cracked or fractured. Thus my invention provides a very strong and substantial shoe which will 65 withstand the rough usage of handling and the strains and blows incident to actual 70 service.

From the foregoing description and the drawings, it will be readily understood that the invention may be used in solid shoes as 75 well as in segmental shoes and in different kinds of segmental and solid car and driver shoes. And I reserve the right to embody the invention in all kinds of shoes and to make all changes in the form, proportion 80 and arrangement of parts within the scope of the following claims.

I claim:

1. A brake shoe comprising a reinforcing back, a plurality of reinforcing strips 85 of reticulated metal arranged on edge to the wearing face of the shoe, means interlocking engaging the back and strips, and a body cast on the back and strips.

2. A brake shoe comprising a reinforcing back having a plurality of slits therein, a plurality of reinforcing strips of reticulated metal engaged in said slits, means for securing the strips to the back, and a body cast 90 on the back and strips.

3. A brake shoe having a reinforcing back with slotted depressions therein, a plurality of reinforcing strips of reticulated metal engaged in said slits, means for securing the strips to the back, and a body cast on the 100 back and strips.

4. A brake shoe comprising a reinforcing back having transverse depressions therein and slits in said depressions extending longitudinally of the back, a plurality of reinforcing strips of reticulated metal engaged 105

in said slits, means for anchoring the strips to the back, and a body cast on said back and strips.

5. A brake shoe comprising a ductile metal reinforcing back having transverse depressions therein and slits in said depressions extending longitudinally of the back, a plurality of reinforcing strips of reticu-

lated metal arranged in an inclined position on edge to the wearing face of the shoe and 10 engaged in said slits, pins anchoring the strips to the back, and a body cast on said back and strips.

JAMES S. THOMPSON.
